DESIGN FOR A HYDRAULIC JACK

Edward M. Pfauser, Wauwatosa, Wis., assignor to
Blackhawk Mfg. Co., Milwaukee, Wis., a corpo-
ration of Wisconsin

Application September 20, 1935, Serial No. 58,626

Term of patent 7 years

To whom it may concern:

Be it known that I, Edward M. Pfauser, a citizen of the United States residing at Wauwatosa, in the county of Milwaukee and State of Wisconsin, have invented a new, original, and ornamental Design for Hydraulic Jacks, of which the following is a specification, reference being had to the accompanying drawing, forming part thereof.

In the drawing, a hydraulic jack embodying my new design is shown in perspective in Figure 1 and in front elevation in Figure 2.

I claim:

The ornamental design for a hydraulic jack as shown.

EDWARD M. PFAUSER.
